LAP TRUING MACHINE

William A. Gunning and George C. Favre, Southbridge, Mass., assignors to American Optical Company, Southbridge, Mass., a voluntary association of Massachusetts

Application September 29, 1948, Serial No. 51,706

14 Claims. (Cl. 90—24)

1

This invention relates to curve generating machines and has particular reference to machines commonly known in the art as lap truing machines used for producing the curved surfaces on tools of the type employed in forming ophthalmic lenses.

One of the principal objects of this invention is to provide a curve generating machine adapted to produce surface curves ranging from 2 to 20 diopters on such articles as laps used in the ophthalmic art.

Another object is the provision of a machine of the above character having improved means for simply and efficiently setting up the machine for automatic and accurate production of the entire range of surface shapes either of single or compound curvatures.

Another object is the provision of an improved machine of the above character employing a graduated scale bar with vernier type slides arranged thereon to facilitate setting up operations and provide a greater degree of accuracy of the curves produced by the machine.

Another object is to provide a machine of the above character having improved control means therefor so constructed and arranged that after being set up to produce a desired surface curvature on a lap or similar article, the machine will employ a rocking motion under control of an electrical power system to automatically generate a curve on the lap in accordance with the machine's settings, and at the conclusion of the cutting operation the machine will be automatically stopped until properly reset by the operator.

Another object is to provide a lap truing machine of the above nature of an extremely simple and compact nature having the operative parts thereof so constructed and arranged that the machine will occupy a minimum of space to accurately produce any surface curvature in the entire range on articles such as laps, the machine, due to the particular construction and arrangement of parts, being further characterized by ruggedness of a heretofore unapproached nature further leading to increased accuracy and efficiency of operation.

Further objects are to provide in a manner as hereinafter set forth a curve generating machine which is comparatively simple in its construction, durable, thoroughly efficient in its use and capable of being readily set up and adjusted for shaping the surfaces of articles such as laps having various surface characteristics.

Other objects and advantages of the invention will become apparent from the following descrip-

2

tion taken in connection with the accompanying drawings, in which:

Fig. 1 is a perspective view of a machine embodying the present invention;

5 Fig. 2 is a fragmentary sectional view through the machine showing the operative parts therein;

Fig. 3 is a fragmentary side view illustrating the means for initially adjusting the device for rendering the machine inoperative;

10 Fig. 4 is a fragmentary sectional view of the operative parts controlled by the adjustment shown in Fig. 3;

Fig. 5 is a fragmentary side elevation of the power driving means for oscillating the machine

15 yoke;

Fig. 6 is a perspective view of the gauge means used for setting up the machine to produce desired curvatures;

Fig. 7 is a fragmentary top plan view of the 20 reversible yoke and its associated parts;

Fig. 8 is a fragmentary view illustrating the means for reversing the machine yoke;

Fig. 9 is a fragmentary top plan view illustrating the use of the gauge means for setting the 25 cutting tool in the yoke for oscillation on a specified radius;

Fig. 10 is a fragmentary top plan view illustrating the means for setting the cutting tool when mounted in the machine tailstock;

30 Figs. 11, 12 and 13 are fragmentary side elevations illustrating various adjustments of the machine to produce various types of surface curvatures;

Fig. 14 is a sectional top plan view of the cam 35 operated switch controlling device;

Fig. 15 shows the clapper box carrying the cutting tool and removed from the device; and

Fig. 16 is a fragmentary sectional view showing the clapper box with the cutting tool in engagement with the surface of a lap to be generated.

45 Machines of this character are commonly known in the ophthalmic art as lap truing machines which are capable of generating different surface curvatures on laps used in forming curved surfaces on lens blanks. Lap truing machines of this nature in the past have been limited as to the number of different surface curvatures which they were capable of producing with 50 the limitations being primarily in weak or shallow curve generations, such curves having relatively long radii. A reason for such limitation is that machines of this nature are commonly used by lens dispensers who, in most instances, carry 55 on their businesses in limited areas in office build-

ings, thus requiring such machines to be restricted as to size. Most prior art machines of this nature, because of the above restrictions, could not produce all of the shapes desired, particularly shallow curved shapes and therefore such laps were in most instances obtained from optical manufacturers who have the facilities for producing them. Although most of the prior art lap truing machines did not produce the full range of curvatures of laps required they did produce most of the essential curve generations. This, however, has been a decided handicap to lens dispensers as considerable time has been lost in the past in having to send to the manufacturer for shallow curve laps when such laps were required.

The present invention, therefore, is adapted particularly to overcome this difficulty through the provision of an improved construction, arrangement of parts, and operative procedure whereby a machine constructed and arranged according to the present disclosure will generate all curves ranging from 2 to 20 diopters, the machine being a further improvement upon the prior art through the provision of simple and improved means for quickly and efficiently adjusting the machine to produce the particular surface curvatures desired.

Referring more particularly to the drawings wherein like characters of reference designate like parts throughout the several views, the lap truing machine embodying the invention comprises a base 15 having a pair of spaced uprights 16 and 17 in which is rotatably supported end portions 18 and 19 of a substantially U-shaped yoke 20. The base 15 has provided in its upper surface a pair of spaced longitudinally extending machined slideways 21 in which is slidably mounted a slide member 22 (Fig. 2) having firmly secured to its under side as by the bolts 23 a tubular member 24. The tubular member 24 has an enlarged portion 25 formed on one side thereof which is provided with a longitudinal opening 26 through which is extended the slide member drive shaft 27, a threaded portion of the drive shaft 27 being in mesh with threads formed in a boss (not shown) on the slide member 22 so that when the shaft 27 is manually or otherwise rotated, as by the handle 28, which is located on the end of the shaft 27 which protrudes from the forward end of the base 15, the slide member 22 will be made to slide in the slideways 21 longitudinally of the machine and in a forward or reverse direction in accordance with the direction of rotation of the shaft 27. The slide member 22 may, if desired, be provided with a chip removing plate 29 to clear the ways 21 of foreign matter and so facilitate the operation of the device and protect the machined surfaces.

The slide member 22 is provided with an undercut portion adjacent one of the slideways 21 in which resides a machined gib 30, the gib 30 being adapted to fit snugly between the member 22 and the slideway 21. The portion of the slide member 22 overlapping the gib 30 has a vertical bore axially aligned with a threaded opening in the gib 30, the concentric bore and opening being adapted to receive a threaded clamp 31 in such a manner that when the slide member 22 is set in a desired position in the slideway 21 the clamp 31 may be turned so that the gib 30 will be drawn upwardly and become wedged between the side of the slideway 21 and the side of the undercut portion of the slide member 22, thus locking the slide member immovably in place.

The bore in the tubular member 24 is vertically aligned with a similar bore in the slide member 22, both bores being adapted to receive an immovable bushing 32 which in turn is adapted to rotatably receive the downwardly extending pivot member 33 of a supporting plate 34 which rotatably resides upon the slide member 22.

The supporting plate 34 is adapted to rotate on the surface of the slide member 22 and about the axis of the pivot member 33 by means of a worm gear 35 (Fig. 2) which is fixedly located on one end of a rotatable drive shaft 36, the worm gear 35 being in mesh with the toothed portion 37 of a ring member 38 which is secured to the lower contour edge of the base portion of the supporting plate 34, as by threaded studs 39. The drive shaft 36 extends forwardly of the machine and is supported near its outer end in a suitable bearing 40. The end of the shaft 36 is provided with a handle 41 so that it may be manually rotated to turn the supporting plate 34 about the axis of the pivot member 33.

The supporting plate 34 is provided with a pair of spaced guideways 42 in which is slidably carried a tailstock 43. The base portion 44 of the tailstock 43 has suitably attached to the lower surface thereof a lug 45 which is adapted to extend downwardly into a longitudinal slotted opening 46 within the supporting plate 34, and which is provided with a longitudinal threaded opening 47 adapted to receive a threaded portion of a forwardly extending shaft 48, the shaft 48 being shaped at its forward end to receive a removable handle so that the shaft 48 can be manually rotated to cause the tailstock to slide longitudinally on the surface of the supporting plate 34. A gib 49 is positioned against the side wall of one of the guideways 42 between the supporting plate 34 and the adjacent portion 50 of the tailstock base portion 44 and in position to be engaged by the end of a stud 51 inserted through the portion 50. By tightening the stud 51 the end thereof can be made to wedge the gib 49 against the wall of the guideway to lock the tailstock against sliding movement on the supporting plate 34.

The upper end of the tailstock 43 has a bearing 52 (Fig. 1) provided therein, the bearing being adapted to support a holder 53 carrying a lap 54 or similar article to be surfaced.

The yoke 20 which is rotatably carried in the upper ends of the spaced uprights 16 and 17 is provided with a bearing 55 in which is slidably mounted a sleeve 56 (Fig. 7), the sleeve being adapted to carry at its forward end a clapper box 57 which in turn supports a suitable cutting tool 58. The sleeve 56 is adjustably located in the bearing 55 in the desired position and can be locked in this position by a handle 59 which is threadedly attached to a threaded stud 60, the stud extending through a pair of spaced bosses 61 formed on the bearing 55. By turning the handle 59 on the stud 60 the bosses 61 will be forced toward each other and thus cause the bearing to fit tightly about the sleeve 56, holding it immovable until the handle is released.

When the yoke is caused to oscillate in the bearings 18 and 19 the tool 58 will consequently be moved in vertical strokes, such motion being imparted through a power driven disc 62 (Fig. 5) having a connecting rod 63 eccentrically and adjustably pivoted thereto. The connecting rod 63 is connected by motion transfer lever means 64 to the yoke 20, and upon rotation of the disc 62 the connecting rod 63 will operate the motion

transfer lever means 64 and cause the yoke 20 and tool 58 to be oscillated in the uprights 16 and 17.

The clapper box 57 carrying the cutting tool 58 is constructed in such a manner that the cutting tool is held rigid as it travels across the face of the lap to produce a cut on the lap when the yoke 20 is caused to oscillate in one direction, and to yield on the return stroke when the yoke is caused to oscillate in the reverse direction. The clapper box 57 is formed with a head portion 133 and an elongated shank portion 134, the shank portion 134 being located within the sleeve 56 carried in the yoke 20 to an extent permitted by a flange 135 formed therearound (Figs. 15 and 16), and is aligned in the sleeve and prevented from rotation therein by a pin 136 which is fixedly located in the sleeve 56 and adapted to reside within opposed slots 137 formed in the walls of the shank portion 134 of the clapper box 57. The head portion 133 is provided with a transverse bore 138 in which is rotatably located a cylinder 139, and is also provided with a slot 140 communicating with the bore 138 and disposed in the portion of the surface away from the shank portion 134. The cylinder 139 is provided with a horizontal opening shaped for the insertion of the cutting tool 58, a set screw 141 being provided to retain the tool 58 in located position within the cylinder 139, the tool being adapted to extend through the slot 140 as shown by full lines in Fig. 16 and having its cutting point disposed on the center line of the clapper box. A notch 142 is formed in the rear portion of the cylinder 139 and a headed stop pin 143 is located in the clapper box head portion in such a position that it will be normally engaged by the vertical wall of the notch 142. This position of the cylinder 139 with respect to the stop pin 143 is maintained during the cutting stroke of the device wherein the force exerted upon the tool 58 as it traverses the face of the lap 54 tends to cause the cylinder 139 to rotate, such rotation being prevented by the stop pin 143. Upon the return stroke, however, as the tool 58 contacts the lap 54 the force exerted will cause the cylinder 139 to rotate about its axis 144 to an extent permitted by the inclined upper surface of the notch 142. This is sufficient to cause the tool to lightly contact the face of the lap and the position of the parts during the return stroke are substantially as shown in dotted outline in Fig. 16. This rotation is against the tension of a coil spring 145 which is located in a longitudinal bore 146 in the shank portion 134 of the clapper box, the spring engaging one end of a sliding pin arrangement 147, which pin has its other end in engagement with a notch 148 formed in the rear portion of the cylinder 139 at a point below the axis point 144 of the cylinder. A stud 149 is threadedly inserted in the bore 146 to retain the spring 145 in position and to enable the tension of the spring to be varied. Thus, the tool 58 will be held rigid during the cutting stroke and will yield upon the return stroke.

Prior to causing the cutting tool 58 to be oscillated, the tool and lap 54 are initially adjusted to provide the proper setup for obtaining the curve generation desired. These adjustments are made through the use of a scale bar or gauge 65 (Fig. 6) which is provided on the front surface with millimeter graduations 66. Adjustable longitudinally on the bar 65 are slides 67 and 68, these slides being of the vernier type and each having conventional vernier graduations 69.

In setting up the machine to provide the lap 54 with a spherical concave surface, wherein the curves in both the horizontal and the vertical meridians are coincident, it is necessary to loosen the clamp for the sleeve 56 by moving the handle 59 in a direction to permit the adjustable sleeve 56 to be moved in the bearing 55 of the yoke 20. Then after setting the slide 68 at the proper reading on the scale bar 65 to indicate the desired radius of curve to be provided in a vertical meridian and locking the slide immovable on the bar by means of the set screw 70, the stem or extension 71 formed integral with one end of the bar 65 is inserted in an opening 72 provided therefor in the yoke 20 (Fig. 9). When inserting the bar 65 in the opening 72 it is important that the bar 65 be inserted so that the pointer 73 on the slide 68 extends in a direction so that it may be engaged by the cutting tool 58 when the sleeve 56 is moved forwardly in the yoke 20. After moving the sleeve 56 so that the end of the tool 58 abuts against the slide pointer 73, the handle 59 may again be operated to lock the sleeve 56 immovable in the yoke bearing 55 as described. This adjustment will result in the tool being so adjusted that it will oscillate on an arc coincident with the radius of the curve desired in a vertical meridian. It is important to note that although the base of the yoke 20 and the bearing 55 are substantially rearwardly disposed from the axis line of the yoke pivotal end portions 18 and 19, the graduations on the scale bar being located so as to position the end of the tool with respect to the horizontal axis line 75 of the yoke pivotal end portions 18 and 19 when the scale bar is positioned as illustrated in Fig. 9. Thus the cutting edge of the tool 58 will oscillate on a radius about the axis line 75 and will produce a curve in accordance with the reading on the scale bar 65 as indicated by the slide 68.

To provide the curve in the horizontal meridian it is necessary to align the vertical axis 74 about which the tailstock 43 rotates so that the radius of such rotation is coincident with the radius of oscillation of the cutting tool 58. This is accomplished by manual rotation of the handle 28 which will cause the slide member 22 and parts mounted thereon to move longitudinally on the base 15. The base 15 is provided on one side thereof at a point adjacent an upper edge with a graduated indicator plate 76 (Fig. 11). The slide member 22 carries a corresponding indicator plate 77 so located that when the slide member 22 is moved longitudinally of the base 15 the indicator plates 76 and 77 will be in vertical alignment when the vertical axis 74 of the supporting plate 34 carried by the slide member 22 is in alignment with the axis of the yoke 20 and tool 58. Thus since the cutting tool 58 oscillates about a radius coincident with the radius about which the lap 54 rotates, it is apparent that the surface of the lap 54, when brought into engagement with the cutting tool 58 by manual rotation of the shaft 48, will have similar curves generated thereon in vertical and horizontal meridians, thus forming the desired spherical concave surface.

After the machine has been set to provide the desired surface curvatures as described suitable control mechanism may be operated to cause the machine to function. Such control mechanism may be any conventional type which will function to cause rotation of the disc 62 and consequent operation of the connection rod 63 attached thereto. This causes, through the motion transfer lever means 64, the oscillation of the cut-

ting tool 58 about the axis 75. The extent of this oscillating movement is sufficient to cause the cutting tool 58 to traverse the entire width of the face of the lap 54 which is to be surfaced. Simultaneous to this function a power driven adjustable stroke pawl 78 engages a ratchet wheel 79 attached to the drive shaft 36 of the mechanism for rotating the supporting plate 34 near the outer end thereof and advances the ratchet wheel an amount equal to the tooth displacement of the pawl. A suitable spring pressed plunger 80 having a portion adapted for engagement with the teeth of the ratchet wheel 79 is adapted to hold the ratchet wheel in advanced position. This causes the ratchet wheel 79 to rotate and to, in turn, rotate the worm gear 35. The worm gear 35 which is in meshed relation with the tooth portion 37 of the ring member 38 secured to the supporting plate 34 will cause the tailstock 43 to be swung in an arc about the pivotal member 33 (Fig. 2). This operation causes the lap 54 to move in a direction substantially normal to the path of movement of the oscillating cutting tool 58 carried by the yoke 20. This is merely general description of a conventional lap truing machine. During such rotary movement of the supporting plate 34 the base 44 of the tailstock 43 is locked in fixed relation with the supporting plate 34 by means of the adjustable studs 51.

When "centering" the machine, that is, positioning the vertical axis 74 of the supporting plate 34 for the tailstock 43 to intersect the axis line 75 of the yoke 20, it is possible to maintain the slide member 22 in fixed relation to the base 15 of the machine without the necessity of relying on the locking clamp 31. This is accomplished by providing a bore 81 extending into the base 15, the bore 81 having the indicator plate 76 located adjacent thereto in such a manner that a semi-circular notch formed in the upper edge of the plate 76 will be aligned with the bore 81, and when the slide member 22 is positioned so that the machine is "centered," a notch on the lower edge of the indicator plate 77 will be aligned with the bore 81 and with the indicator plate 76. Thus by inserting a plug 82, which may be attached permanently to the machine base 15 as by a chain 83 (Fig. 1), in the bore 81 when the indicator plates 76 and 77 are aligned the slide 22 can be rendered immovable on the base until the plug 82 is removed.

The above describes the forming of a spherical concave surface on the lap 54.

It is to be understood that prior to causing the cutting tool to reciprocate transversely of the face of the lap 54 and to simultaneously cause said lap to move in a path substantially normal to the path of movement of the cutting tool, the lap and cutting tool are initially adjusted relative to each other. The lap tailstock 43 is initially adjusted in a sidewise direction an amount sufficient to clear the cutting tool 58 prior to starting the cutting operation whereby the cutting tool will transverse the entire surface area of the lap.

In producing a spherical convex surface on the lap 54 the setup is opposite to that used for producing a spherical concave surface. The lap 54 and cutting tool 58 are interchanged, with the tool 58 and clapper box 57 being inserted in the tailstock 43 and the lap residing in the sleeve 56 in the yoke 20. Thus, in the operation of the machine the lap will oscillate vertically in accordance with the action of the yoke 20 while

75 the cutting tool will rotate with the tailstock to produce the convex surface on the lap.

To set the machine to produce the desired spherical convex surface curvature of the slide 22 is adjusted longitudinally of the slideway 21 by manual rotation of the handle 29 to a position wherein the indicator plate 77 is aligned with the indicator plate 76 and with the bore 81 whereby the locating plug 82 may be positioned in said bore to retain the notched portions of the indicator plates 76 and 77 in fixed alignment with each other. The scale bar 65 is then positioned against one side of the supporting plate 34 and is held in said position by inserting its stem 71 extending rearwardly and inwardly of an opening in a boss 89 formed integral with the side of the supporting plate 34, see Fig. 11. The slide 68 may then be moved longitudinally of the scale bar to the position thereon in accordance with the radius of curvature desired as established by the proper graduations 66 on the scale, or this setting may be formed prior to securing the scale in position on the supporting plate 34. An L-shaped gauge 84, as shown in Fig. 10, having a hand grip knob 65 on the side thereof and having a pin-like protuberance 88 adjacent one end thereof is positioned on the tailstock 43 with its longitudinal side portion 86 lying within a longitudinal groove 87 formed in the side of the tailstock 43 and with its pin-like protuberance 88 fitting within an opening in said tailstock. The tool 58 is then adjusted longitudinally in the tailstock until its cutting edge is in abutting relation with the base portion of the gauge. This establishes the distance between the end of the tool 58 and the tailstock 43 and simultaneously locates the end of the tool at a given fixed position with respect to the indicator line on the plate 90, which position is established according to the graduations 66 on the scale 65 so that when the position of said graduations 66 is fixed by placing the stem 71 in the boss 89 the given designated graduations on the scale will, during the adjustment of the member 68 longitudinally thereof into alignment with given graduations on the scale, automatically position the tool at the proper distance from the center line 74 when the indicator line on the plate 90 is thereafter moved into alignment with the notch 91. This latter adjustment is obtained through the use of a detachable handle (not shown) which is secured to the shaft 48 and by means of which the said shaft can be rotated to move the tailstock 43 longitudinally of the supporting plate 34 to a position wherein the said indicator line on the plate 90 is in alignment with the notch 91.

It is to be understood that a different sequence of adjustments may be employed in order to obtain the above setting and it is not of necessity, for example, that the slide 22 be first adjusted to the proper position as established by the indicator plates 76 and 77, which position automatically locates the axis 74 in intersecting relation with the axis 75 of the yoke 20 as this adjustment could be performed after the tool position was established through the use of the L-shaped gauge, etc.

After the above adjustments have been accomplished and in order to generate the curve on the lap the handle 59 is adjusted to a position wherein the sleeve 56 carrying the lap 54 may be moved longitudinally in the yoke 20. This movement is such as to bring the lap into cutting relation with the tool 58. The handle 59 is then manipulated to secure the sleeve in the yoke and to retain the

lap in fixed position of adjustment. Subsequent to this positioning of the lap in desired relation with the tool the machine is set into operation as hereinbefore described to produce the desired spherical convex surface on the lap.

In producing a spherocylinder concave surface on the lap 54 the lap will be positioned in the tailstock 43 with the tool located for oscillation with the yoke 20. In this setup the tool is adjusted by using the scale bar 65 as hereinbefore described to control the radius about which it will oscillate. After adjusting the tool, the scale bar 65 is removed from the yoke 20 and is then brought into a position as indicated in Fig. 12 wherein, with the slide 67 set at the proper graduation 66 to indicate the radius of base curve desired, the scale bar 65 will rest upon a shelf 92 formed on the machine base 15 adjacent and parallel to one of the guideways 21 thereof. The shelf 92 is provided with an upwardly extending pin 93 which, in this particular adjusting operation, resides in a comating opening formed in the bottom of the slide 68. The stem portion 71 of the scale bar 65, in this instance, is positioned to extend in a direction forwardly of the machine. The handle 28 may be operated to cause the slide member 22 to be moved on the base 15 to a position wherein the indicator line on a plate 94 will become aligned with a notch 95 provided in the slide 67. This will establish a radius about which the tailstock 43 will rotate to produce a curve in one of the major meridians of the lap known or designated as the base curve and which has a radius different from the radius of the curve in the other major meridian of the lap known or designated as the cylinder curve, which latter radius is established by setting the end of the cutting tool at the desired distance from the center line of the bearings 18 and 19.

In producing a spherocylinder convex surface on the lap, the lap and cutting tool are interchanged as in producing a spherical convex surface. The scale bar 65 is then brought into position upon the shelf 92 with the pin 93 being inserted in the opening in the bottom of the slide 68 and with the stem portion 71 of the scale bar now extending in a direction rearwardly of the machine. Then by operating handle 28, the slide member 22 can be moved on the base 15 until the indicator line on the plate 94 is in alignment with the notch 91 in the scale slide 68 (Fig. 13). After this latter adjustment has been accomplishment the scale bar 65 is then positioned against the side of the supporting plate 34 with its stem portion 71 extending within the bore of the boss 89 as illustrated in Fig. 11. The tailstock can then be adjusted so that the indicator line on the plate 90 and notch 91 on scale 68 is aligned as hereinbefore described. Then the lap can be moved in the yoke 20 into proper relation with the cutting tool so that the desired spherocylinder convex surface is obtained.

The foregoing procedure is used when producing all surface curvatures from 3 diopters to 20 diopters. However, when it is desired to produce curves below 3 diopters it is necessary to alter the machine somewhat to accommodate the extra length radii necessary to produce the curves. This alteration is made so that the machine and parts carried thereby will occupy a minimum of floor space and is accomplished by first removing the sleeve 56 from the yoke 20 and rotating the yoke 180° in its bearings 18 and 19 to the position shown in dotted outline in Fig. 7. In order to make this change the yoke 20 is disconnected

from the motion transfer lever means 64. The means 64 includes an operating arm 96 (Fig. 8) which is operatively mounted on a shaft 97 rotatably supported in the upper end of the upright 11. The operating arm 96 is provided with a bifurcated extension or arm 98 and a diametrically opposed bifurcated arm 99. In the construction of the machine for operation as hereinbefore described, the shaft 97 carrying the yoke 20 is provided with a bifurcated member 100 fixedly secured adjacent the arm 98 to and rotatable with said shaft 97. To operatively connect the motion transfer means 64 to the yoke 20 so that the yoke will oscillate in its bearings in response to the action of the connection rod 63, the member 100 is connected to the arm 98 by means of an eyebolt and nut connection 101. However, to alter the machine to accommodate curves of longer radii the connection 101 is disengaged from the arm 98 and the yoke member 100 together with the yoke 20 is rotated 180° to the position indicated in dotted outline in Fig. 8, wherein the member 100 will be located adjacent the arm 99 and connected thereto by the connection 101 as it was previously connected to the arm 98. By so changing the machine the yoke 20 will be positioned as indicated in dotted outline in Fig. 7 and will be operated in the manner hereinbefore described. The sleeve 56 may then be reinserted in the yoke bearing 55 and, due to the new position of the yoke, may be projected toward the forward end of the machine an amount greater than was possible with the yoke positioned in the previous manner.

To produce a spherical concave surface of less than 3 diopters on the lap 54 the scale bar 65 is used to position the cutting tool 58 with respect to the radius of curve desired. However, since the yoke is in a different position than formerly the slide 68 is aligned with a series of millimeter graduations on the reverse side of the bar from the graduations 66, this series of graduations being figured so that the radius will be established from the axis line 75 so that the proper curve will be generated. The machine will then be "centered" as previously described. This will permit a spherical concave surface to be formed on the lap.

To generate a spherical convex and spherocylinder convex surfaces of less than 3 diopters, the tool and lap are reversed and the machine set up similarly to the setup used for 3-20 diopter curves using the graduations on the reverse side of the scale bar 65.

To generate spherocylinder concave surfaces of less than 3 diopters the machine is set up similarly to the setup used for 3-20 diopter curves except that the graduations on the reverse side of the scale bar 65 are used for establishing the desired cylinder curve radius.

In most prior art machines of the type embodying the present invention the cycle of movement of the lap and tool relative to each other during the cutting of the surface, as, for example, the cycle of movement of parts simulating the supporting plate 34 of the present invention which carries the tailstock 43 about its pivot member 33, is generally constant regardless of the radius of curvature of the surface being generated on the lap. This cycle, in such prior art machines, was established by the required amount of movement of the lap and tool relative to each other during the producing of a surface curvature of the shortest possible radius. A surface of a long radius of curvature requires much less

movement than that required for shorter radii and, therefore, a considerable loss of time was encountered due to the waste motion of the lap and tool relative to each other throughout that period wherein the said lap and tool were not in cutting engagement with each other. The present invention overcomes the above objection of most prior art machines of this nature in that the movement of the lap and tool relative to each other, during the cutting operation, introduced by moving the supporting plate 34 carrying the tailstock 43 about the axis of its pivot 33 is controllable so that its cycle of movement will be only that required to produce the surface shape on the particular lap being surfaced. This is accomplished by providing means for adjusting the lap and tool to required initial position at the start of the cut and by automatically stopping the movement of the lap and tool relative to each other at the completion of the cut.

This means comprises a control arm 102 located adjacent one side of the supporting plate 34 (Figs. 2, 3, 4 and 5), the control arm 102 being fixedly secured to one end of a shaft 103 rotatably mounted through the side walls of the plate 34 and carrying a lever arm 104 thereon. The control arm 102 is positioned longitudinally of the supporting plate 34 in such a manner that it will be engaged by an adjustable member 105 which is adjustably located on the base 44 of the tailstock 43 immediately above the control arm 102. The control arm 102 is normally inclined and has its outer end disposed higher than its supported end. However, when the tailstock 43 is moved on the supporting plate 34 the member 105 will ride longitudinally along the upper edge of the control arm 102, and will cause the arm 102 to be moved downwardly as the tailstock moves rearwardly of the machine. As the arm 102 moves about the axis of the shaft 103 this movement will be transmitted to the lever arm 104, the free end of which is shaped for engagement with the upper end of a vertical cam shaft 106 which is disposed within a vertical central bore 107 in the pivot member 33. The shaft 106 is provided with means such as a key 108, a portion of which is adapted to reside within a vertical slot 109 in the narrowed lower end of the bore 107, see Fig. 2. Thus, the cam shaft 106 may slide vertically in the member 33 and will rotate with the member 33 as the member is caused to rotate by movement of the supporting plate 34. A coil spring 110 resides within the bore 107 and around the shaft 106, a collar 111 secured as by a pin 112 to the upper end of the shaft serves to retain the spring 110 in this position, the lower end of the spring abutting upon the shelf formed in the bore 107 adjacent this lower end. Thus, when the lever arm 104 forces the cam shaft 106 downwardly, the movement is against the force exerted by the coil spring 110. The rearward movement of the tailstock 43 and consequent downward movement of the control arm 102, lever arm 104, and cam shaft 106 is indicated in dotted outline in Figs. 3 and 4.

The cam shaft carries at its lower end a cam member 113 which has a cam surface 113a of a controlled contour shape, the member 113 being suitably secured to the shaft 106 as by a nut or hub 114. Depending from the slide member 22 are a pair of fixed supporting arms 115 (Figs. 2 and 14) which carry therebetween a shaft 116. An operating member 117 is rotatable about the shaft 116 and is provided with spaced branches 118 and 119, the branch 118 extending beneath

the cam member 113 and having an adjustable follower 120 located at the end thereof in engagement with the irregular surface 113a of the cam member 113. The other branch 119 has a stud 121 located thereon which is adapted to retain one end of a coil spring 122, which spring is located on a similar retaining stud 123 carried by a switch arm 124. The switch arm 124 is located on the shaft 116 adjacent the member 117, the arm 124 and member 117 being connected for limited cooperative movement by a tongue and notch arrangement indicated by numeral 125 in Fig. 14. A spring member 126 connects the operating member 117 to a fixed portion of the device such as one of the arms 115 and serves to keep the follower 120 on the branch 118 in constant engagement with the irregular surface 113a of the cam member 113 as well as to relieve the pressure on the micro-switch 127 located on the arm 124. Thus, the downward movement of the cam member 113, and rotation thereof when the handle 41 is operated to locate the lap and cutting tool with respect to one another for the start of the cycle of the surfacing operation, will position the follower 120 on a low spot of the irregular cam surface 113a of the cam 113. Then upon operation of the machine the cam 113 will rotate with the supporting plate 34. This will cause the cam follower 120 to be lowered as the high point of the cam surface 113a is approached, which in turn causes the branch 119 and switch arm 124 to be lowered.

The normally closed micro-switch 127 which is secured to the switch arm 124 is provided with a conventional switch operating plunger member 128 which, upon downward movement of the switch arm 124, is adapted to engage an adjustable contact member 129 located on an extension 130 formed on or secured to one of the arms 115. The micro-switch 127 is suitably connected in an electrical circuit to the motor 132, which motor operates through conventional mechanism to rotate the drive disc 62 causing oscillation of the yoke 20 and also drives the adjustable stroke pawl mechanism 78, which simultaneously causes intermittent rotation of the supporting plate 34 about the axis of its pivot member 33, in a direction transversely to the oscillation of the yoke to feed the lap and tool relative to each other. The arc in which the lap or tool is rotated by the yoke, depending upon whether a convex or concave lap is being formed, controls the shape of curve formed in that meridian and the arc in which the lap or tool supporting plate 34 is moved by the intermittent action of the pawl mechanism 78 controls the shape of the surface formed in that meridian. Thus, when the entire surface of the lap has been shaped, the cam 113, which has been rotated simultaneously with the movement of the supporting plate 34, will cause a point on said high portion of the cam surface to be moved into engagement with the follower 120 causing said follower to be depressed and simultaneously will cause the switch 127 to be moved to a position wherein the plunger member 128 thereof will in turn cause the switch to be operated to open the circuit. This causes the motor to become de-energized and will stop the operation of the machine. The function of the mechanism for controlling the operation of the machine so as to control the cycle of movement required to form a completely generated surface on the lap is as follows:

When the tailstock 43 is initially adjusted lon-

itudinally of the supporting plate 34 to align the indicator on the plate 90 with the notch 91, as shown in Fig. 11, according to the setting desired of the machine and to establish the curvature to be formed in the horizontal meridian of the lap, the member 105 carried by the tailstock base 44 and which is constantly in engagement with the control arm 102, will cause said control arm to be moved upwardly or downwardly depending upon the direction of said longitudinal movement. This movement of the control arm 102 will automatically cause the cam member 113 to be raised or lowered a controlled amount to fix its position during the forming of the surface on the lap and this position will vary in accordance with the radius of curve to be generated in the horizontal meridian of the lap. This initial upward or downward movement of the cam member 113 simultaneously causes the cam follower 120 to be raised or lowered to a fixed initial position in proportion to the initial upward or downward movement of said cam and will therefore cause the subsequent rotation of the cam 113 during the operation of the machine to move the high point thereof in a direction toward the cam follower 120 whereupon said high point will depress the follower and cause the plunger member to trip the switch to open position whereupon the motor will be de-energized and stop the operation of the machine. Therefore, when the tailstock 43 is adjusted longitudinally of the supporting plate 34 to a fixed position for the generation of a curve of a relatively short radius, the member 105 carried by the tailstock will move to a position on the control arm 102 which allows said control arm to move upwardly and thereby cause the lever 104 to raise and permit the cam 113 to be simultaneously lifted to an initial fixed position according to the radius of curve to be generated, it being understood, of course, that the above described setting is controlled by the use of gauge means such as set forth above. The shaft 36 is then manually rotated by means of the hand grip member 41 to move the lap and tool to initial adjacent relation to each other for starting the operation of the machine. This rotation of the shaft 36 and, in turn, the rotation of the supporting plate 34, will impart a rotary movement to the cam 113 and will move said cam into proper starting relation with the follower 120, that is, it will position the high point on the cam surface 113a at a proper distance from the cam follower 120 to insure the full cycle of movement of the tailstock 43 required to complete the surface prior to having the high point on the cam engage the cam follower 120 to trip the switch to de-energize the motor.

When the tailstock 43 is adjusted to a fixed position to generate a curve of a relatively long radius the member 105 in engagement with the control arm 102 will move to a position on said arm causing said arm to be depressed in proportion to said movement and in turn move the cam 113 in a downward direction and to a fixed position determined by the arc of the curve to be generated. The function of the device in producing this curve is similar to that described above and by reason of the fact that the cam is initially moved downwardly to accommodate a curve of a longer radius this downward movement will initially depress the plunger 128 of the switch an amount whereby only a relatively small rotary movement of the cam member 113 will be required to move the high point thereof into engagement with the follower 120 whereupon further depress-

ing of the plunger 128 will take place. This causes the switch to be tripped to open the circuit and deenergize the motor at the proper time required for stopping the machine at the completion of the forming of the surface of long radius. With this arrangement the time interval of the operation of the machine is only that required to complete the surface of any desired curvature.

Since it might be desirable, however, to manually rotate the supporting plate 34 beyond the point at which the machine is rendered inoperable, there is provided a stop 131 adjustably located in the extension 130 adjacent the contact 129. The stop 131 is positioned to be engaged by the microswitch 127 with the coil spring 122 absorbing the strain imposed upon the device by the cam follower 120 when the follower is forced to follow the irregular surface of the cam 113 to a point even higher than that necessary to operate the switch 127, this excessive movement also being permitted by the connection 125, thus preventing damage of the parts of the device.

From the foregoing description it will be seen that simple, efficient and economical means have been provided for accomplishing all of the objects and advantages of the invention. By providing the improved features described, it can be seen that the present invention is a considerable improvement over prior machines used for generating curved surfaces on articles such as laps by providing a machine of extremely compact nature which will produce curves ranging from 2 to 20 diopters which formerly required the use of large, bulky space-taking machines. Also are provided means for more accurately and quickly setting up a machine of this type and means for automatically stopping the operation of the machine after completion of a surfacing operation regardless of the radius of curvature being generated. Such a machine, as disclosed herein may be easily adjusted, maintained and repaired.

While certain novel features of the invention have been shown and described and are pointed out in the annexed claims, it will be understood that various omissions, substitutions and changes in the formation and details of the device illustrated and in its operation may be made by those skilled in the art without departing from the spirit of the invention.

We claim:

1. A machine for generating a spherical or compound curved surface on an article comprising the combination of a base having a pair of spaced uprights thereon, a first supporting member pivotally connected with said uprights, pivot means connecting said first supporting member with said uprights, said first supporting member being mounted for oscillating movement about the axis of the pivot means, a second supporting member adjustably mounted on said base for movement in a direction toward and away from said uprights, a pivot member connected for movement with said second supporting member and having its axis substantially perpendicular to the axis of said pivot means, said second supporting member being mounted for movement about the axis of the pivot member, retaining devices on said supporting members, one of said retaining devices supporting a cutting tool and the other of said devices supporting work to be engaged by said cutting tool, power means for imparting an oscillating movement to the first supporting member and its associated retaining device about the axis of said pivot means and

for imparting a rotative movement to the said supporting member and its associated retaining device about the axis of said pivot member, a circuit connecting said power means with a source of electrical energy, circuit control means in said circuit, and means for automatically rendering said power means effective only throughout the angle of movement of one of said retaining devices relative to the other of said retaining devices necessary to complete a surface of required curvature on the work, said means comprising a spindle rotatable with said pivot member and adjustable longitudinally thereof in response to the adjustment of said second supporting member toward or away from said uprights and a cam member on and rotatable with said spindle, said circuit controlling means being operatively associated with said cam member in such manner as to energize and de-energize the power means at controlled positions of movement of one of said retaining devices relative to the other.

2. A machine for generating a spherical or compound curved surface on an article comprising the combination of a base having a pair of spaced supports thereon, a supporting member pivotally connected with said supports, pivot means connecting said supporting member with said supports, the supporting member being mounted for oscillating movement about the axis of the pivot means, a second supporting member adjustably mounted on said base for movement in a direction toward and away from said supports, a pivot member connected for movement with said second supporting member and having its axis substantially perpendicular to the axis of said pivot means, said second supporting member being mounted for movement about the axis of the pivot member, an upright carried by and longitudinally adjustable of said second supporting member, retaining devices on said first supporting member and said upright, one of said retaining devices supporting a cutting tool and the other of said devices supporting work to be engaged by said cutting tool, power means for imparting an oscillating movement to the first supporting member and its associated retaining device about the axis of said pivot means and for imparting a rotative movement to the second supporting member and its associated retaining device about the axis of said pivot member, a circuit connecting said power means with a source of electrical energy, a control arm carried by said second supporting member and operated by said upright upon adjustment of said upright on said second supporting member, a spindle rotatable with said pivot member and in operative engagement with said control arm for adjustment longitudinally of said pivot member, a cam member rotatable with said spindle, and circuit controlling means in said circuit under control of said cam member and operatively connected to said power means for automatically rendering said power means effective only throughout the angle of movement of one of said retaining devices relative to the other of said retaining devices necessary to complete a surface of required curvature on the work.

3. In a machine for generating a spherical or compound curved surface on an article, the combination of a base having a pair of spaced uprights thereon, an article supporting member mounted on said base, a substantially U-shaped yoke pivotally connected with said uprights, the base portion of said U-shaped yoke carrying an article to be positioned with respect to the arti-

cle carried by said supporting member, pivot means connecting said yoke to said uprights for oscillating movement about the axis of the pivot means, said pivot means comprising bearings located adjacent the ends of said yoke and rotatably disposed within said uprights, one of said bearings having a connection member disposed for movement therewith, power means for causing oscillation of said yoke, and including an operating arm mounted for oscillating movement coaxially with said yoke and having diametrically opposed extensions formed thereon, connection means for connecting said connection member to one of said extensions, said connection means being of a detachable nature so as to permit disengagement of said connection member from the extension, rotation of said yoke independently of said operating arm to cause the base portion of the yoke to extend toward or away from said supporting member depending upon the initial position thereof, and attachment of the connection member to the opposed extension, whereby the article carried by the yoke will be positioned toward or away from said supporting member in accordance with the position of the yoke.

4. In a machine for generating a spherical or compound curved surface on an article, the combination of a base having a pair of spaced uprights thereon, a first article supporting member mounted on said base, a second supporting member pivotally connected with said uprights and having its article retaining portion extending away from said first supporting member and carrying an article positioned for engagement with the article carried by said first supporting member, pivot means connecting said second supporting member to said uprights for oscillating movement about the axis of the pivot means and consequent coaxial movement of the article carried by said second supporting member about a radius determined by the distance between said article and the axis of the pivot means, said pivot means comprising bearings located adjacent the ends of said second supporting member and rotatably disposed within said uprights, one of said bearings having a connection member disposed for movement therewith, power means for causing oscillation of said second supporting member and including an operating arm mounted for oscillating movement coaxially with said second supporting member and having diametrically opposed extensions formed thereon, connection means for connecting said connection member to one of said extensions, said connection means being of a detachable nature so as to permit disengagement of said connection member from the extension, rotation of said second supporting member independently of said operating arm to position its article retaining portion toward said first supporting member and permit the article carried thereby to be oscillated about a radius longer than that allowable by the initial position of the second supporting member and attachment of the connection member to the opposed extension.

5. In a machine for generating a spherical or compound curved surface on an article, a base having a pair of spaced uprights thereon, a support pivotally mounted upon said base for oscillating movement about the axis of its pivot, a supporting member adjustably mounted on said base for pivotal movement about an axis substantially perpendicular to the axis of said support and having indicating plates adjustably

carried thereby, a slideway formed on said base and carrying said supporting member for movement toward and away from said support, retaining devices on said support and said supporting member, one of said retaining devices supporting the article to be surfaced and the other of said devices supporting an article used for forming the surface on the article to be surfaced, said articles having portions thereof adapted for operative engagement with each other, locating means carried by the base adjacent said slideway, locating means carried by the support adjacent its retaining device, locating means carried by the supporting member adjacent its retaining device, gauge means comprising an elongated bar member having an engagement end portion shaped for engagement with the locating means carried by said support and said supporting member, said bar member having graduations thereon and a slide mounted for longitudinal movement therealong for alignment with said graduations, said slide having an alignment portion adapted to be aligned with the article carried by the retaining device in said support when said end portion is in engagement with the locating means of said support whereby the distance between the axis of the support and the article carried by the support may be established, said slide member further being adapted for alignment with one of the indicating plates on said supporting member when said end portion is in engagement with the locating means carried by the supporting member whereby the distance between the engaging portions of the articles and the axis of the supporting member may be established, said slide further having an engagement portion adapted to be engaged with the locating means carried by the base, and a second slide carried by said bar member, the other of said indicating plates on the supporting member being adapted to be brought into alignment with said second slide so as to further determine the spacing of the engaging portions of the articles from the axes of the support and supporting member.

6. In a machine for generating a spherical or compound curved surface on an article, a base having a pair of spaced uprights thereon, a support pivotally mounted upon said base for oscillating movement about the axis of its pivot, a supporting member adjustably mounted on said base for pivotal movement about an axis substantially perpendicular to the axis of said support and having indicating plates adjustably carried thereby, a slideway formed on said base and carrying said supporting member for movement toward and away from said support, retaining devices on said support and said supporting member, one of said retaining devices supporting the article to be surfaced and the other of said devices supporting an article used for forming the surface on the article to be surfaced, said articles having portions thereof adapted for operative engagement with each other, locating means carried by the base adjacent said slideway and comprising a shelf having a pin member located near one end thereof, locating means in the nature of an opening in the support adjacent its retaining device, locating means comprising a boss having an opening formed therein, the boss being carried by the supporting member adjacent its retaining device, gauge means comprising an elongated bar member having an engagement end portion shaped for engagement with the openings in the locating means carried by said support and said

supporting member, said bar member having graduations thereon and a slide mounted for longitudinal movement therealong for alignment with said graduations, said slide having an alignment portion adapted to be aligned with the article carried by the retaining device in said support when said end portion is in engagement with the opening in the locating means of said support whereby the distance between the axis of the support and the article carried by the support may be established, said slide member further being adapted for alignment with one of the indicating plates on said supporting member when said end portion is in engagement with the opening in the locating means carried by the supporting member whereby the distance between the engaging portions of the articles and the axis of the supporting member may be established, said slide further having an opening adapted to be engaged by the pin member of the locating means carried by the base when the gauge means is positioned on the shelf thereof, and a second slide carried by said bar member, the other of said indicating plates on the supporting member being adapted to be brought into alignment with said second slide so as to further determine the spacing of the engaging portions of the articles from the axes of the support and supporting member.

7. In a machine for generating a spherical or compound curved surface on an article, a base, a support on said base for the article to be surfaced and a second support pivotally mounted upon said base for oscillating movement about the axis of its pivot, said second support supporting means for yieldably carrying a cutting tool in operative engagement with the article, said means comprising a clapper box having a shank portion supported in the retaining device and a head portion disposed in a direction toward the article to be surfaced, a cylinder member mounted for rotation within said head portion and having the cutting tool fixedly secured therein, said cutting tool having its cutting point aligned with the longitudinal axis of the clapper box, stop means for preventing rotation of said cylinder when pressure is exerted upon the cutting tool from one direction, and resilient means for maintaining the cylinder in located position with respect to the stop means for yieldably permitting rotation of the cylinder when pressure is exerted upon the cutting tool from the opposite direction.

8. In a machine for generating a spherical or compound curved surface on an article, a base having a first support mounted thereon for carrying the article to be surfaced, and a second support pivotally mounted upon said base for oscillating movement about the axis of its pivot, said second support supporting means for yieldably carrying a cutting tool in operative engagement with the article, said means comprising a clapper box having a shank portion supported in the retaining device and a head portion disposed in a direction toward the article to be surfaced, a cylinder member mounted for rotation within said head portion and having the cutting tool fixedly secured therein, said cutting tool having its cutting point aligned with the longitudinal axis of the clapper box, stop means comprising a pin member fixedly located in said head portion and adapted to be engaged by a notch formed in said cylinder for preventing rotation of the cylinder when pressure is exerted upon the cutting tool from one direction, and resilient means

for maintaining the cylinder in located position with respect to the stop means and for yieldably permitting rotation of the cylinder when pressure is exerted upon the cutting tool from the opposite direction.

9. In a machine for generating a spherical or compound curved surface on an article, a base having a first support mounted thereon for supporting the article to be surfaced, and a second support pivotally mounted upon said base for oscillating movement about the axis of its pivot, said second support supporting means for yieldably carrying a cutting tool in operative engagement with the article, said means comprising a clapper box having a shank portion supported in the retaining device and a head portion disposed in a direction toward the article to be surfaced, a cylinder member mounted for rotation within said head portion and having the cutting tool fixedly secured therein, said cutting tool having its cutting point aligned with the longitudinal axis of the clapper box, stop means comprising a pin member fixedly located in said head portion and adapted to be engaged by a notch formed in said cylinder for preventing rotation of the cylinder when pressure is exerted upon the cutting tool from one direction, and resilient means comprising a resilient spring member disposed within said shank portion under compression and a pin arrangement urged by said resilient spring member toward a second notch formed in said cylinder for maintaining the cylinder in located position with respect to the stop means and for yieldably permitting rotation of the cylinder when pressure is exerted upon the cutting tool from the opposite direction.

10. A surface generating device of the character described comprising the combination of a base, a first supporting member mounted on said base for oscillating movement about a given axis, a second supporting member mounted for swinging movement about an axis substantially perpendicular to the axis of said first supporting means, one of said supporting members being adapted for supporting a cutting tool and the other being adapted for supporting work to be engaged by said cutting tool, adjusting means for moving the second supporting member toward and away from the axis about which said first supporting member is mounted for oscillating movement, and drive means acting on said second supporting member for imparting swinging movement thereto about its axis, means for energizing and de-energizing the action of said drive means, and control means swinging with the second supporting member and adjustable in response to the position to which said second supporting member is adjusted relative to the axis about which said first supporting member oscillates, said energizing and de-energizing means being operably associated with the control means in such manner as to energize and de-energize the action of the drive means at controlled positions of movement of one of said supporting members relative to the other, whereby said drive means will be effective only throughout the angle of movement of one of said supporting members relative to the other necessary to complete a surface of required curvature on the work.

11. A surface generating device of the character described comprising the combination of a base, a first supporting member mounted on said base for oscillating movement about a given axis, a second supporting member mounted for swinging movement about an axis substantially per-

pendicular to the axis of said first supporting means, one of said supporting members having holding means for supporting a cutting tool and the other having holding means for supporting work to be engaged by said cutting tool, adjusting means for moving the holding means on a respective supporting member toward and away from the axis about which said member is mounted for movement in accordance with the curve desired to be generated by the tool on the work, and drive means for imparting oscillating movement to the first supporting member about its axis and for imparting swinging movement to the second supporting member about its axis, control means for energizing and de-energizing the action of said drive means, and cooperative means carried by the second supporting member and its respective holding means operable on said control means in response to the position to which said holding means is adjusted on said second supporting member to energize and de-energize the action of the drive means at controlled positions of movement of one of said supporting members relative to the other, whereby said drive means will be effective only throughout the angle of movement of one of said supporting members relative to the other necessary to complete a surface of required curvature on the work.

12. A surface generating device of the character described comprising a pair of supports, one being adapted to support a work member having a surface to be generated and the other being adapted to support a tool member, one of said supports being mounted for oscillating movement about a given axis and the other being mounted on a table rotatably mounted for movement about an axis disposed approximately normal to the axis about which the first support oscillates, said second support being mounted on said table for adjustment toward and away from the axis of said table to vary the radius about which the member carried thereby is swingable by rotation of the table in accordance with the surface to be produced on the work, means for rotating the table to position the member carried by the second support to one side of the member carried by the first support where, by subsequent oscillation of the first support and rotation of the table, the tool may be caused to generate a surface on the work, and drive means for rotating the table and oscillating the first support to obtain said generating action, means for de-energizing the action of said drive means, control means carried by the table and operable on said de-energizing means upon rotation of the table a controllable amount, said control means being adjustable to vary the amount of rotation of the table required before it will operate the de-energizing means, and said adjustment of the control means being responsive to the adjustment of the second support on the rotatable table relative to the axis thereof whereby the action of the drive means to rotate the table may be automatically controlled so as to be effective only sufficient to generate the surface on the work.

13. A surface generating device of the character described comprising a pair of supports, one being adapted to support a work member having a surface to be generated and the other being adapted to support a tool member, one of said supports being mounted on a base for oscillating movement about a given axis and the other being mounted on a table rotatably mounted on said base for movement about an axis disposed approximately normal to the axis about which the

first support oscillates, each of said supports being adjustable toward and away from the respective axis about which it is moveable to vary the radius about which the respective member carried thereby is swingable in accordance with the curved surface desired to be produced on the work, means for rotating the table to position the member carried by the second support member to one side of the member carried by the first support where, by subsequent oscillation of the first support and rotation of the table, the tool may be caused to generate a surface on the work, and drive means for rotating the table and oscillating the first support to obtain said surface generating action, means for de-energizing the action of said drive means, control means carried by the table and operable on said de-energizing means upon rotation of the table a controllable amount, said control means being adjustable to vary the amount of rotation of the table required before it will operate the de-energizing means, and said adjustment of the control means being responsive to the adjustment of the second support on the rotatable table relative to the axis thereof whereby the action of the drive means to rotate the table may be automatically controlled so as to be effective only sufficient to generate the desired curve on the work.

14. A surface generating device of the character described comprising a base, a pair of supports, one being adapted to support a work member having a surface to be generated and the other being adapted to support a tool member, one of said supports being mounted on said base for oscillating movement about a given axis, a slide member adjustably mounted on the base for movement in directions toward and away from said axis about which the first support is mounted for oscillating movement, a table rotatably mounted on said slide member for movement about an axis disposed approximately normal to the axis about which the first support oscillates, said second support being mounted on said table for adjustment toward and away from the axis of said table and said first support having means for adjusting the separation of the member carried thereby relative to the axis about which it

5 oscillates to permit the radius about which the respective member carried thereby is swingable in accordance with the curvature of surface desired to be produced on the work, means for rotating the table to position the member carried by the second support member to one side of the member carried by the first support, adjustment means for bringing said members into relative positions where, by rotation of the table, the 10 member carried by the second support may be moved transversely of the member carried by the first support to generate the desired surface, and drive means for rotating the table and oscillating the first support to obtain said generating action, 15 means for de-energizing the action of said drive means, control means carried by the table and operable on said de-energizing means upon rotation of the table a controllable amount in a direction to move the member carried by the second 20 support from said starting position to one side of the member carried by the first support in a direction transversely thereof, said control means being adjustable to vary the amount of rotation of the table required before it will operate the 25 de-energizing means, and said adjustment of the control means being responsive to the adjustment of the second support on the rotatable table relative to the axis about which the table is rotatable whereby the action of the drive means to rotate 30 the table may be automatically controlled to be effective only sufficient to generate the desired surface on the work.
